UNITED STATES PATENT OFFICE.

MIKE SZONDEROWSKI, OF THREE RIVERS, MASSACHUSETTS.

DESIGN FOR A BASKET.

57,395.

Specification for Design. Patented Mar. 15, 1921.

Application filed May 11, 1920. Serial No. 380,670. Term of patent 3½ years.

To all whom it may concern:

Be it known that I, MIKE SZONDEROWSKI, a citizen of Poland, residing at Three Rivers, in the county of Hampden and State of Massachusetts, have invented a new, original, and ornamental Design for Baskets, of which the following is a specification, reference being had to the accompanying drawing, forming a part thereof.

The figure is a perspective view of my basket, showing my ornamental design.

I claim:

The ornamental design for a basket, as shown.

MIKE SZONDEROWSKI.
